UNITED STATES PATENT OFFICE.

MAURICE LANDAU AND ARMEN TRAXLER, OF ST. LOUIS, MISSOURI.

DESIGN FOR A SHOE-STAND.

SPECIFICATION forming part of Design No. 23,192, dated April 10, 1894.

Application filed March 12, 1894. Serial No. 503,863. Term of patent 14 years.

to all whom it may concern:

Be it known that we, MAURICE LANDAU and ARMEN TRAXLER, of St. Louis, in the State of Missouri, have invented and produced a new and original Design for a Shoe-Stand, of which the following is a full, clear, and exact description, reference being had to the accompanying drawings, forming a part hereof.

In the drawings: Figure 1 is a side elevation of a shoe stand, embodying our design, and Fig. 2 is a sectional plan view of same, the section being taken on the line 2—2 of Fig. 1.

Our design consists of a circular base or pedestal 1, from which arises a vertical body

2 rectangular in cross-section and surmounted by an apical body 3 having the general contour of an acorn. The sides of the vertical body are provided with a series of transverse projections 4, the outer portions of which are curved upward.

What we claim is—

The design for a shoe-stand herein shown and described.

In testimony whereof we affix our signatures in presence of two witnesses.

MAURICE LANDAU.
ARMEN TRAXLER.
